ERNESTO ABBIATI, OF NEW YORK, N. Y., ASSIGNOR TO HIMSELF AND
JOHN N. LONGHI, OF SAME PLACE.

Letters Patent No. 72,439, dated December 24, 1867.

IMPROVED TRACK-CLEARER.

The Schedule referred to in these Letters Patent and making part of the same.

TO ALL WHOM IT MAY CONCERN:

Be it known that I, ERNESTO ABBIATI, of the city, county, and State of New York, have invented a new and improved Track and Street-Cleaner; and I do hereby declare that the following is a full, clear, and exact description thereof, which will enable those skilled in the art to make and use the same, reference being had to the accompanying drawings, forming part of this specification, in which—

Figure 1 represents a side elevation, partly in section, of my invention.

Figure 2 is a horizontal sectional view of the same, the plane of section being indicated by the line $z z$, fig. 1.

Figure 3 is a horizontal sectional view of the same, the plane of section being indicated by the line $y y$, fig. 1.

Similar letters of reference indicate corresponding parts.

This invention relates to a new device for clearing railroad-tracks and streets from snow, and consists in the use of a revolving horizontal disk carrying oscillating wings, which wings are drawn in and out by the action of crank-shafts revolved by means of gear-wheels from the shaft to which the disk is secured. This shaft is secured to the front part of a truck, which moves in front of the locomotive or car, or to the front part of a wagon or car, and receives rotary motion from one of the wheels of the locomotive, car, or wagon, or from any other suitable device. The disk is suspended close above the level of the street or above the track to be cleared, and has a cutting-edge, whereby it is enabled to pass easily through the snow, and to separate the same from the ground or track. The wings, then, as they arrive at the front of the disk, begin to be gradually moved out, and, as they arrive at the side, they are moved quite out, and throw the snow, from the disk, over the side of the track. Brushes, moving behind the disk, and in front of the wheels, clear the track completely from all particles of snow.

A represents a vertical shaft, fitted through a stationary arm, B, which is secured to the front of a car, or locomotive, or wagon, or to the front of a truck, C, which is arranged and moves in front of the car, locomotive, or other vehicle. The shaft A is suspended by means of a sleeve, a, which is provided with friction-rollers, d, running on the arm B, as shown, and carries a pulley or gear-wheel, b, near its upper end, by means of which it receives rotary motion from one of the axles of the car, truck, locomotive, wagon, or from some other suitable mechanism. To the lower end of the shaft A is secured a disk, D, which has a sharp edge, and which is suspended close above the rails to be cleaned, or above the surface of the street. In the disk D are bearings for four, more or less, upright crank-shafts, E E. The upper ends of these crank-shafts carry pinions, F F, which mesh into a stationary pinion, G, formed on or secured to the stationary arm B. Thus, as the shafts E are revolved around the axle A, they are also, at the same time, revolved around their own axles. To the disk D are also pivoted, with their ends, four, or more or less, curved wings, H, which are, by means of rods e, connected with the cranks on the shafts E. Thus, as the device is set in motion, the wings will be drawn in and pushed out.

The device being in front of the locomotive, the wings will move all the obstacles lying on the disk D off the same, while the disk gathers all obstacles upon the surface of the rail or street. The respective diameters of the wheels F and G determine how frequently the wings are moved out during each revolution of the shaft A.

The device shown in the drawing would throw the snow to one side of the track, and would, therefore, be best adapted for clearing a double track. Where two such devices are arranged in front of a car or other vehicle, the snow will be thrown to two sides.

For clearing railroad-tracks, it is advisable to have suitable brushes, I I, in rear of the disk, for the purpose of having the track completely prepared for traffic. These brushes may be secured to a revolving shaft, or to the framework of the vehicle, as may be desired.

I claim as new, and desire to secure by Letters Patent—

1. The application, to a track and street-cleaner, of oscillating wings H H, operated by means of crank-shafts E E, to which planetary motion is imparted, substantially as herein shown and described, and for the purpose specified.

2. The oscillating wings H, when arranged upon and operating in combination with a revolving disk, D, all made and operating substantially as herein shown and described.

3. The track-cleaner, when consisting of the revolving disk D, carrying the oscillating wings H, in combination with the brushes I I, all made and operating substantially as and for the purpose specified.

ERNESTO ABBIATI.
